UNITED STATES PATENT OFFICE.

EUGENE H. TAYLOR, OF LYNN, MASSACHUSETTS, ASSIGNOR TO THE CUSHMAN PAPER BOX MACHINE COMPANY, OF PORTLAND, MAINE.

MACHINE FOR MANUFACTURE OF PAPER BOXES.

SPECIFICATION forming part of Letters Patent No. 542,225, dated July 2, 1895.

Application filed September 25, 1890. Serial No. 366,128. (No model.)

To all whom it may concern:

Be it known that I, EUGENE H. TAYLOR, of Lynn, county of Essex, State of Massachusetts, have invented an Improvement in Machines for the Manufacture of Paper Boxes, of which the following description, in connection with the accompanying drawings, is a specification, like letters and figures on the drawings representing like parts.

10 The machine to be herein described is an improvement on that described in United States Patent No. 418,690, dated January 7, 1890; and it has for its object to improve and simplify the construction of the parts whereby 15 the durability and strength of the machine is increased and the adjustment of the parts facilitated, as will be described.

20 The particular features of this invention will be described in the following specification and pointed out in the claims at the end thereof.

Figure 1 is a partial view of the delivery end of a paper-box-making machine embodying my present invention. Fig. 2 is a detail 25 chiefly to show the lip-turner shaft and adjustable lip-turners; Fig. 3, an end view of the devices shown in Fig. 2; Fig. 4, an enlarged section across the lip-turner shaft. Fig. 5 is a partial plan view, it showing about one-half 30 of the machine at the delivery end, the part broken away at one side being a duplicate of that shown; Fig. 6, a partial plan view looking at the machine farther back, or at the commencement of the side guides, the said 35 figure, in connection with Fig. 5, showing the gearing for adjusting the side guides positively and simultaneously. Fig. 7 is a partial section in the irregular dotted line x' , Fig. 5. Fig. 8, in perspective, shows one of 40 the end plates detached. Fig. 9 is a partial vertical longitudinal section chiefly to show the "former" and follower, which are omitted from the other figures; Fig. 10, an enlarged detail of a sliding rack and its actuating devices. Fig. 11 shows one of the locking 45 devices in plan. Fig. 12 is a detached view showing the guide 14 and parts attached to it; and Fig. 13 is a detail showing one end of the guide 14, the attached projection 19, stop 50 21, and a track below it. Fig. 14 is a partial transverse section in the line x^6 , Fig. 5, the

worm 6 and screw A^2 being, however, in elevation; and Fig. 15 is a partial longitudinal section in the line $x' x^{10}$, the shaft 16 being omitted.

55 One feature of this invention consists in making the lip-turners laterally adjustable on their operating-shafts inside of the bearings for said shafts, which bearings are located at the ends of said shaft, whereby they are adapted to co-operate with formers of different length.

Another feature of this invention consists in the combination, with stationary tracks, the side guides between which the blanks are placed and moved, blocks longitudinally adjustable on the guides, and a horizontally-adjustable stop for each block, of parallel screw-shafts which engage the said guides near their opposite ends, other shafts and gearing connecting the said shafts so that the side guides may be adjusted simultaneously toward or from each other.

The side frames A, the bed or table plate A', the pressure-screw shafts $G' G^2 G^3 G^4$, the 75 gears 33, one at each end of each of said shafts, the racks G^5 , having the projections 37, the latches 39, pivoted thereon, the pressure-heads $H H'$, the end turning plates or wipers d^7 , the side turners or wipers d^8 , the yoke h^8 , the 80 guide-rods A^2 , the nuts 61 thereon, the adjustable plates B^{22} and B^{19} on the table-plate, the slide-rod h' , its attached follower h , and the former F are and may be all substantially as described in said United States Patent No. 418,690. It will also be understood that each 85 half of the machine will contain like parts, with the exception that in practice the ejecting device (not shown) is solely at one side of the machine.

90 Each pressure-head $H H'$ has at each of its ends two like nuts H^3 , making four nuts for each head, each nut fitting threads on one of the pressure-shafts for moving the said pressure-heads. Each nut is mounted loosely in 95 the pressure-head, so as to rotate therein, and has attached to it a gear H^4 , and each pair of gears H^4 is engaged and rotated by one intermediate gear 4, adapted to rotate on a stud H^{20} , (see Fig. 7 in section and Fig. 5 by dotted 100 lines,) carried by the pressure-head. There are two of these intermediate gears 4 for each

pressure-head and they mesh together, and one intermediate gear has attached to it a worm-gear 5, (see Figs. 5 and 7,) which is engaged and adapted to be rotated by a worm on a vertical shaft 6, having its bearing in a part of the pressure-head, said shaft 6 at its upper end being provided with a suitable handle or hand piece 7, by which it may be turned by hand whenever it is desired to adjust the pressure-heads toward or from each other, to adapt the end wipers or plates d^7 , carried by them, to the thickness of the blank being made into a box or cover on the former.

With the pressure-heads $H H'$ properly adjusted to the size of the blank they are reciprocated toward and from each other during the completion of each box and toward and from the usual former by the reciprocation of the slide-racks G^5 , as provided for in the said patent.

In the patent referred to the end wiper-plates were rigidly attached to an angle-plate adjustably secured to the pressure-head; but in case of any irregularity in thickness of the blank on the former the thinner portion of the blank to be pressed into shape was not subjected to sufficient pressure, and frequently the corner where the stock was thinnest would not be properly pressed smooth or united. To obviate this trouble I have attached each end wiper-plate d^7 to a block 8, having, preferably, a convexed back and adapted to rock on or about a vertical pivot 9, (see Figs. 5 and 8,) the convexed part entering a proper concavity in the pressure-head as a seat. The ends of this pivot enter and take bearing in lugs 10, attached to the pressure-head at bottom and top by suitable screws, as 12. The uppermost lug 10 has a countersunk hole, in which enters a locking-pin 13, resting on a spring 13^x , (see Figs. 8 and 14,) having a tapered point, (see Fig. 7,) the said pin normally acting to center or hold the block 8 with the face of the end wiper at right angles to the face of the wiper-plates d^7 . In case, however, of any variation in thickness of the paper of the blank bent over the end of the former F and between it and the inwardly-moving end wiper d^7 , then the said block, owing to the fact that it is loosely pivoted, is free to turn on the pivot 9 and adapt itself to the varying thickness of the blank, the conical point of the spring-actuated locking device or pin at such time, by its action against the edge of the conical-shaped hole in the lug 10, depressing the said locking device.

The blanks from which the boxes are to be made are in practice laid in a pile, as provided for and represented in the patent referred to, and while in this pile are kept in place by means of guides, which are held adjustably in place by set-screws. In this my present invention I have devised means whereby the said guides at each end of the pile are adapted to be adjusted simultaneously, which is a matter of great convenience and saving of time, and whereby, also, the

said guides may always be kept in the same relative parallelism under all adjustments. To accomplish this adjustment each end of each side guide 14 is provided with a nut 15, which nuts are entered by the right and left threads of the guide-adjusting screw-shafts 16 17. (See Figs. 1, 5, and 6.) These shafts have, respectively, bevel-gears $16' 17'$, which are engaged by bevel-gears $16^2 17^2$ at the ends of a shaft 18, so that rotation of the shaft 16 by the handle 16^3 will effect the simultaneous and equal adjustment toward or from each other of the two guides 14, one at each end of the machine. Each guide 14 referred to (see Fig. 6) has at its inner end a slotted projection 19, (see Figs. 12 and 14,) adjustably attached to it by a screw 20, (shown in dotted lines, Fig. 6,) which is extended through a longitudinal slot in the guide 14, so that the said projection may be adjusted in the direction of the length of the guide, in order to adapt it to the size of the blank in the pile. The patented machine referred to had substantially such a projection, but herein said projection is provided with a vertically-placed stop 21, which is made adjustable on the said projection 19 (see Figs. 1 and 6) toward and from the said guide, a screw 21^x holding it in position, such stop serving to contact with the rear edges of the blank above the track B^{12} , fully described in the said patent and designated by like letters, on which the undermost blank of the pile rests when being wet and pasted, there being a track for each end of the blank, but herein I have shown only one track. The blank is pushed along the tracks by a suitable feeding device. By making this stop adjustable, as described, so that it may be placed just over the track, it prevents any blank from being pulled backward under the stop by the returning feeder, as would be possible should the blank sag at either side of the track and the stop be placed at a distance to one side the track so as not to be hit by the blank. So, also, this location of the stop enables the usual wetters and pasters to rise and not interfere with or strike against the stops. This guide 14 has attached to it near its delivery end, by screw 24, (see Fig. 1,) a longitudinally-adjustable block 25, having a vertically-extended guide-finger 26, against which the front edge of the blank is arrested, and up which it travels when the former, as described in the said patent, rises to lift the blank and pinch it between its own top and the under side of the co-operating follower h above it.

Referring to Figs. 1, 12, and 13, it will be noticed that the guide-plates 14 are provided at their lower sides with inwardly-projecting lips t^4 , on which lips ride the ends of the foremost blank as it is being carried forward by the usual feeder from the bottom of the pile of blanks, the inner end of the said lip being bent downwardly at t^5 , next the pile of blanks.

To reciprocate the racks G^5 , I employ a

slide-bar A²⁴ at each side of the machine; but herein I shall describe but one such bar. Each bar A²⁴ has a pin A²³, which is engaged by the upper end of a connecting-rod A²², and at its upper end said bar has an adjustable bunter A²⁵, provided with a shoulder 40, which, as it rises, bunts against the projection 37 of the rack G⁵ and catches onto the latch 39 to pull down the rack as the slide-bar A²⁴ descends. The slide-bar A²⁴ slides in a sleeve-like portion A²⁶ of a sliding cross-head F⁵, which has a sliding fit on the guide-rods A², one at each side of the machine, the said cross-head in practice carrying the former, about which the blank is bent and shaped to form a box or cover. These parts are the same as in the said patent, and are designated by like letters. In the said patent the slide-bar A²⁴ was at times locked to the said sleeve A²⁶ to lift the cross-head F⁵, and thereafter was unlocked, and while the cross-head was locked was further lifted to lift the racks G⁵ to put on the pressure. In the said patented machine the locking device, (herein marked 41,) was slid in one and then in the other direction by two elbow-levers actuated by vertical levers, which were struck by a rotating projection. In this present invention I have dispensed with the said elbow-levers and their actuating devices and have effected the longitudinal reciprocation of the locking device by increasing the bevel at the ends of the locking device and by providing the slide-bar A²⁴ and the guide A² with correspondingly-beveled surfaces 28 and 29, the said bevels being preferably at an angle of substantially forty-five degrees.

Referring to Fig. 10, it will be supposed that the slide-bar A²⁴ is on its upstroke. Now, as soon as the bevel 28 thereon meets the beveled end of the locking device the latter is pushed to the right and stopped with its inner end against the guide-rod A². The bevel 28 acting on the locking device causes the cross-head F⁵ to thereafter rise in unison with the slide-bar until the inner end of the locking device enters the notch 30, it gradually sliding over the bevel 29. This inward movement of the locking device by the bevel 28 frees the slide-bar from the locking device and cross-head, so that in the farther upward movement of the slide-bar, while the cross-head remains at rest and locked in position by the locking device, the bunter meets the projection 37 and lifts the rack G⁵ to rotate the pressure-screws and put on the pressure. As the slide-bar is drawn down, the bunter catches the latch 39 and pulls the rack down to remove the pressure from the box in the former, and as the rack reaches its lowest position the bevel 28 passes below the end of the locking device, and thereafter, due to the weight of the cross-head and the beveled surface 29, on which the inner end of the locking device rests, the said locking device is thrust to the left out of the notch 30 and the cross-head descends, and also the slide-bar A²⁴, the

latter being pulled down by its connecting-rod.

The lips at the ends of the side of the box blank have to be turned in and placed in close contact with the ends of the former, preparatory to turning down and over upon them the portions of the blank to constitute the ends of the box.

Patent No. 420,901, granted February 4, 1890, to G. H. Cushman and myself, contains lip-turners and means for actuating them at the proper times by the box blank itself. Such means, also herein shown, consisted essentially of rock-shafts B, having their journals at the extremities thereof in bearings in suitable ears or stands B⁵⁰, (see Figs. 2 and 9,) connected to the outsides of the side wiper-plates d³, the said rock-shafts being toothed or roughened for a portion of their circumference and being flattened for another portion, they deriving their movement by the contact of the box against the said toothed surface. (See Figs. 2 to 4.) The rock-shafts herein shown carry near their ends, between the toothed surfaces and bearings, lip-turners n, the hubs n⁴ of which are split and clamped on the splines 32 at the ends of the shaft by suitable set-screws 31, inserted through ears of the said hubs. These lip-turners are thus made adjustable longitudinally on the said rock-shafts inside of the bearings for use with boxes of different size, for a different former must be used, and in the construction shown in the patent referred to the bearings for the rock-shaft would prevent the employment of different formers and also prevent the adjustment of the lip-turners to co-operate therewith.

The side wiper-plates d³, to which the lip-turner shafts B are connected, are provided with shanks 34, rectangular in cross-section, which fit a guide-way on the yoke h³. Each shank 34 in practice is provided at its outer end with a threaded-hole, in which is entered the threaded end of an adjusting-screw 35, which may be rotated, but is restrained from longitudinal movement by a plate 300, entering an annular groove in the shank of the screw.

The threaded pressure-screws, the pressure-head, and sleeves or nuts loosely mounted and rotatable in the said pressure-head, and herein shown and described, are not claimed herein, as they form the subject-matter of claims in another application filed by me November 17, 1893, Serial No. 491,273, and allowed December 10, 1894.

I claim—

1. The pressure head, combined with the rocking block and its attached end wiper plate, and with a yielding locking device for the said block, substantially as described.

2. The stationary tracks B¹², the side guides having nuts at their ends, longitudinally adjustable blocks 19 on said guides, and the horizontally adjustable stop 21 for each block, and the cross shafts provided with right and left hand screws with which the said nuts are

engaged, combined with the connecting shaft 18, and engaging bevel gears on said connecting or cross-shafts whereby the said side guides are made adjustable simultaneously 5 by rotation of the connecting shaft, substantially as described.

3. The adjustable side guide, and its longitudinally adjustable block 19, combined with the horizontally adjustable stop 21, and tracks 10 to support the blank to operate, substantially as described.

4. The combination with the "former," and the rock-shaft B having splined ends, and bearings therefor at the extremities of said 15 ends of the lip-turners n provided with hubs laterally adjustable on the splined ends of

said rock-shaft inside of said bearings, and set screws to clamp the hubs thereon to thereby adapt said lip turners to boxes of different length, substantially as described. 20

5. The guide A² having a beveled notch, the cross-head having a sleeve, and a bevel ended locking device, combined with the slide bar having a bevel surface 28, to operate, substantially as described. 25

In testimony whereof I have signed my name to this specification in the presence of two subscribing witnesses.

EUGENE H. TAYLOR.
